UNITED STATES PATENT OFFICE.

HOMER E. SHEPARD, OF ROCHESTER, NEW YORK, ASSIGNOR OF ONE-THIRD TO JACOB E. RENNER, OF SAME PLACE.

DRIVING MECHANISM FOR CYCLES.

SPECIFICATION forming part of Letters Patent No. 622,085, dated March 28, 1899.

Application filed December 31, 1897. Serial No. 665,056. (No model.)

To all whom it may concern:

Be it known that I, HOMER E. SHEPARD, of Rochester, in the county of Monroe and State of New York, have invented certain new and useful Improvements in Driving Mechanism for Cycles; and I do hereby declare the following to be a full, clear, and exact description of the same, reference being had to the accompanying drawings, forming a part of this specification, and to the reference-numerals marked thereon.

My present invention relates to driving mechanism particularly adapted for use on cycles whereby the advantages of a high gear are obtained with considerable power and without the necessity of having the pedals to which the rider's feet are applied traverse a large circle; and to these ends it consists generally in the employment of two cranks 20 provided with pedals which are adapted to operate as levers alternately near the periphery of a driving-wheel connected with the traction-wheel of the vehicle, whereby the rider is enabled to apply considerable power 25 by reason of increased leverage; and it further consists in certain improvements whereby the mechanism is adapted to bicycles in a comparatively simple manner, all as will be hereinafter fully described, the novel features 30 being pointed out in the claims at the end of this specification.

In the drawings, Figure 1 is a side elevation of a cycle driving device embodying my improvements; Fig. 2, a sectional view on the line *x* *x* of Fig. 1; Fig. 3, an elevation of a portion of the opposite side of the machine from that shown in Fig. 1; Fig. 4, a vertical sectional view through the crank-hanger and frame; Fig. 5, a sectional view on the line *y* *y* of Fig. 1.

Similar reference-numerals indicate similar parts.

The main frame of the cycle to which my invention is to be applied may be of the usual 45 or any suitable construction; but I prefer to form or connect the front tube 1 directly with the rear fork 21 at an angle or curve, in which angle is arranged the sleeve 2, constituting a tubular hanger and occupying the same relative position as the crank-hanger on an ordinary bicycle. The tube or seat-post 31 ex-

tends through the hanger and is secured to the frame and to the hanger 2 itself by brazing or in any other suitable manner, as shown particularly in Fig. 4. This construction 55 brings the hanger quite low, which is advantageous, besides strengthening the parts without adding materially to the weight thereof. Upon the outer periphery of the hanger 2, at its ends, are mounted adjustable bearing-collars 3, and outside of these collars are collars 4, the space between the collars being filled by antifriction-balls 5. The collars 4 are adjustably connected to rings 6 6^x, one being mounted on each side of the bicycle-frame, each of the rings 6 6^x having connected to or formed with it a crank 7 7^x, upon which are adjustably mounted pedals 8 of any suitable construction. The rings 6 6^x are not connected directly with each other, excepting 70 through the sprocket or driving wheel, as hereinafter described.

9 indicates a large driving-wheel, preferably in the form of a sprocket and connected by a chain 10 with the traction-wheel of the 75 cycle and mounted rigidly upon a tubular axle 11, extending through the bearing-sleeve 12 in the frame and passing through the crank-rings 6 6^x, but below and in rear of the center thereof, as shown. The bearing-sleeve 12 80 is secured in position between the seat-post and the rear fork, which extends at an angle to the front tube, as shown in Fig. 4. This connection may be formed entirely by brazing, if desired; but I prefer the use of the 85 screws 40 in addition, as shown. At the opposite end of the axle 11 from the wheel 9 is secured an arm 13, and as a means for removably connecting the wheel, axle, and arm I provide a central spindle 14, having upon 90 its end nuts 15 for confining the parts, as shown particularly in Fig. 2. Adjustable bearings are provided between the axle 11 and the sleeve 12 by balls 16, arranged between adjustable collars 17 and 18 on the axle 95 and sleeve, respectively. The centers of rotation of the rings 6 6^x, carrying the cranks, are eccentric of the center of rotation of the wheel 9 and preferably above and forward of said center, and the wheel is provided near 100 its periphery and on the outer face with two antifriction-rollers 19 and 20, the latter pref-

erably having a rib at its periphery coöperating with a corresponding groove formed on the lower side of the cranks, preferably that on the right-hand side of the machine, said 5 crank being offset and extending through an aperture in the wheel and between the rollers, as shown in Figs. 1 and 2. The crank 7^x on the opposite side of the machine is also grooved on one side in a manner similar to 10 the crank 7, and the crank 13 also has rollers 19^x and 20^x thereon similar to those on the wheel, but on diametrically opposite sides of the center of the latter from said last-mentioned rollers. The relative length of the 15 cranks and the radius of the sprocket-wheel may be altered, as desired; but it is preferable that the radius of the sprocket be the greater, as by this means a high gear with economy in the power applied may be obtained without excessive movement of the 20 pedals.

When power is applied to the forward pedal, the crank to which it is connected will operate as a lever, having its fulcrum at the lower 25 side of the bearing between the ring and hanger and will operate upon the sprocket-wheel near its periphery, thereby giving increased power during at least a portion of its rotation, and, when the left pedal (the one on 30 the farther side in Fig. 1) is forward the power applied to it will be transmitted through the crank 13 and the axle to the sprocket also, the maximum effect being obtained when the cranks are in line with the centers of the rings 35 and wheel.

While I have shown and described the driving-wheel 9 as a sprocket connected to the traction-wheel of the vehicle by a chain, it will be understood that any other form of 40 wheel could be employed and other connections, such as gearing, employed.

The arrangement of parts described is simple and enables me to obtain the advantage of a high-geared machine with the expenditure 45 of comparatively little power and without causing the operator's feet to traverse a large circle.

I claim as my invention—

1. The combination with the cycle-frame 50 embodying the continuous front tube and rear fork, the tubular hanger, the seat-post extend-

ing through the hanger and connected to the frame, and the sleeve eccentrically arranged in the hanger, of the axle journaled in the sleeve, the wheel thereon, and the ring on the hanger having the cranks connected to the wheel. 55

2. The combination with the tubular hanger, the bearing-collars thereon, the rings surrounding the hanger having the cranks, 60 the bearing-collars on the rings, and the balls between the collars, of the driving-wheel, axle and ball bearings therefor arranged within and eccentrically of the hanger, the crank on the axle and rollers on the crank and wheel 65 between which the ring-cranks operate to drive the axle and wheel.

3. The combination with the hanger, the ring-cranks journaled thereon, the continuous tubular axle and bearings therefor inside 70 the hanger, and eccentric thereof, of the driving-wheel mounted on one end of the axle-independent of the bearings, the crank on the opposite end of the axle independent of the bearings, the removable spindle or bolt extending through the axle, a nut on the end thereof, said spindle operating to hold the wheel and crank on the axle, and connections between the ring-cranks and the axle-crank and driving-wheel. 75

4. The combination with the tubular hanger, the rings mounted on opposite ends of the hanger, and the offset cranks on the rings having pedals at their outer ends, of the axle journaled in the hanger and eccentrically 80 thereof, the sprocket-wheel at one end of the axle having an aperture through which one of the ring-cranks extends, and the rollers with which said ring-crank engages, and the crank on the axle opposite the wheel, having 85 the rollers with which the corresponding ring-crank engages, the point of connection between the ring-cranks and the axle-crank and driving-wheel being between the rotary centers of said cranks and the pedals, whereby 90 the cranks will operate as lengthened levers in propelling the driving-wheel, substantially 95 as described.

HOMER E. SHEPARD.
